US0D1065734S

(12) **United States Design Patent** (10) Patent No.: **US D1,065,734 S**
(45) Date of Patent: ** Mar. 4, 2025

(54) **DUST SEPARATOR FOR DUST MITE VACUUM CLEANERS**

(71) Applicant: **FASTER BETTER EASIER, LLC,**
Orion Township, MI (US)

(72) Inventors: **Thomas E. Huntley**, Auburn Hills, MI
(US); **Joseph A. Huntley**, Greenville,
SC (US)

(**) Term: **15 Years**

(21) Appl. No.: **35/518,775**

(22) Filed: **Oct. 27, 2022**

(80) **Hague Agreement Data**

Int. Filing Date: **Oct. 27, 2022**

Int. Reg. No.: **DM/226393**

Int. Reg. Date: **Oct. 27, 2022**

Int. Reg. Pub. Date: **Oct. 27, 2023**

(51) **LOC (15) Cl. 15-05**

(52) **U.S. Cl.**

USPC **D32/25**

(58) **Field of Classification Search**

USPC D32/1, 15, 16, 17, 18, 21, 23, 25, 31

(57) **CLAIM**

The ornamental design for a dust separator for dust mite vacuum cleaners, as shown and described.

DESCRIPTION

1. Dust separator for dust mite vacuum cleaners

1.1 : Perspective

1.2 : Front

1.3 : Back

1.4 : Top

1.5 : Bottom

1.6 : Left

1.7 : Right

1.8 : Bottom Perspective View

1 Claim, 8 Drawing Sheets
